UNITED STATES PATENT OFFICE.

LEONARD S. LAMB, OF SEATTLE, WASHINGTON.

HEEL PROTECTOR.

Application filed June 22, 1925. Serial No. 38,706.

To all whom it may concern:

Be it known that I, LEONARD S. LAMB, a citizen of the United States, residing at Seattle, in the county of King and State of Washington, have invented a certain new and useful Improvement in Heel Protectors, of which the following is a specification.

My invention relates to improvements in heel protectors or pads of a form adapted to be inserted within a shoe to protect the heel of the wearer and the object of my invention is to provide a heel protector of simple and efficient construction that may be quickly and easily secured within the heel portion of a shoe so as to form a smooth and comfortable pad whereon the heel of the foot may rest.

Another object is to provide a heel protector which embodies a pad of protective material, as leather, secured to a plate of metal which is adapted to be made fast to the inside of the shoe at the place where the heel rests and serving to prevent nails and tacks from working up into the shoe and being of such form so that it will assume a permanent curvature best adapted to fit the heel of the foot of the wearer when in use.

I accomplish these objects by devices illustrated in the accompanying drawings, wherein—

Figure 1 is a top plan view of a heel protector constructed in accordance with my invention;

Fig. 2 is an inverted plan view of the same;

Fig. 3 is a sectional view on line 3, 3 of Fig. 1; and

Fig. 4 is a view in longitudinal section showing my heel protector applied to a shoe.

Referring to the drawings throughout which like reference numerals indicate like parts, 5 designates a pad of protective material, as leather, shaped to fit within the heel of a shoe 6, and preferably tapered so that it is thinner at its forward end. The rear end of the pad 5 is secured by a rivet 7 to a metal plate 8 that is also shaped to fit

the heel of a shoe and is preferably slightly smaller than the pad 5, as shown in Figs. 1 and 2. The plate 8 is provided around its rear end with a plurality of radial slots 9 which weaken that portion of the plate 55 sufficiently so that it will assume a permanent concave shape corresponding to the shape of the wearer's heel when in use.

The plate 7 is further provided with two, more or less, perforations 10 through which 60 tacks 11 may be driven, as shown in Fig. 4, to secure the heel protector within a shoe. The single rivet 7 permits the pad 5 to be turned up out of the way while driving the tacks 11. 65

In applying my heel protector it is placed within a shoe with the rear end pressed tightly back against the rear of the shoe, the pad 5 is held up out of the way and the tacks 11 are driven down into the shoe 70 heel. The pad 5 being pivotally secured at the rear end, by rivet 7 to the plate 8 leaves said pad free to be turned slightly, if necessary, to correctly position the same within the shoe heel after the plate 8 has been 75 tacked to the shoe heel. The plate 8 is thick enough to prevent ordinary heel nails from punching upwardly therethrough and thus serves as an armor to protect the heel of the wearer. The slots 9 are comparatively narrow so that there is little danger of the heel 80 nails working up through said slots and said slots cause the plate 8 to assume a permanent curvature to fit the heel of the foot. The plate 8 not only forms an armor 85 but also provides a quick and easy means for securing the heel protector within a shoe. The pad 5 is thick enough to form a comfortable pad on which the heel of the foot may rest without elevating the heel into 90 an uncomfortable position.

The foregoing description and accompanying drawings clearly disclose a preferred embodiment of my invention but it will be understood that this disclosure is 95 merely illustrative and that such changes in the device may be resorted to as are within the spirit and scope of the invention.

What I claim is:

1. A heel protector, embodying a metal 100

plate, and a pad of protective material secured at one point to said plate and arranged to be turned up to allow said plate to be tacked within the heel portion of a shoe.

2. A heel protector, embodying a metal plate shaped to fit within the heel portion of a shoe and having perforations toward its forward end through which securing means

may be inserted and driven into the heel of the shoe, a pad of protective material shaped to fit within the heel portion of a shoe, and a rivet securing the rear of said pad to the rear of said plate.

In witness whereof, I hereunto subscribe my name this 10th day of June A. D. 1925.

LEONARD S. LAMB.
